UNITED STATES PATENT OFFICE.

EARL P. MAYHEW, OF SAN DIEGO, CALIFORNIA.

GOLD-SAVING AMALGAMATOR.

1,221,347.

Specification of Letters Patent.

Patented Apr. 3, 1917.

Application filed July 13, 1916. Serial No. 109,118.

To all whom it may concern:

Be it known that I, EARL P. MAYHEW, a citizen of the United States of America, residing at San Diego, in the county of San 5 Diego and State of California, have invented certain new and useful Improvements in Gold-Saving Amalgamators, of which the following is a specification.

This invention relates to gold saving 10 amalgamators and it has for its object the provision of an amalgamator of the mercury type in which the gold bearing sand, gravel and water may be continuously passed through a pipe and in its passage 15 forced through a number of bodies of mercury, together with means whereby the bodies of mercury with the trap fed gold may be withdrawn at any time without interfering with the continuous operation of 20 the apparatus.

Further objects and advantages of the invention will be set forth in the detailed description which now follows.

In the accompanying drawing

25 Figure 1 is a side elevation of an amalgamator or gold saving device constructed in accordance with the invention, and

Fig. 2 is a transverse vertical sectional view therethrough upon line 2—2 of Fig. 1, 30 with some of the parts broken away.

Like numerals designate corresponding parts in all of the figures of the drawing.

Referring to the drawing 5 designates a serpentine pipe the coils of which are disposed in a vertical plane. It will, therefore, be seen that this pipe comprises a plurality of goose-necks. The lower bends of these goose-necks form pockets 6 adapted to receive bodies of mercury indicated in 35 dotted lines in Fig. 1. When gold bearing sand, gravel and water are forced through the pipe 5 and through the several bodies of mercury, the fine gold particles are trapped and held by the mercury in the pockets 6.

40 While I have shown three of these pockets, it is apparent that any desired number may be employed. To render it possible to introduce mercury or to remove the mercury and gold from said pockets without interfering with the continuous operation of the 45 device, each of the downwardly extending goose-necks is intersected by vertically dis-

posed piping, each comprising a cross 7, a shut-off valve 8 disposed above the cross, a receiving chamber 9 above the shut-off valve 55 8, a shut-off valve 10 above the receiving chamber and a funnel 11 above the shut-off valve 10. Below the cross 7, there is a shut-off valve 12 and below the shut-off valve 12, there is a storage chamber 13, the latter carrying a shut-off valve 14 and a discharge nozzle 15. When it is desired to introduce mercury to any of the pockets 6 without interfering with the remainder of the pipe 5 or with the continuous operation of the mercury in any of the other of said pockets 6, the shut-off valve 8 controlling the pocket that is to be filled is closed and the shut-off valve 10 is opened. Mercury may then be poured through the funnel 11 into the receiving chamber 9. Then the shut-off valve 10 is closed and the shut-off valve 8 is opened, which permits the mercury to flow from the receiving chamber 9 into the pockets 6. When the mercury in the pockets 6 75 has been in use long enough to render it desirable to remove the gold therefrom, shut-off valve 12 is opened and, at the same time, shut-off valve 14 is closed. This permits the mercury to flow into the storage chamber 80 13. Thereupon shut-off valve 12 is closed and if the shut-off valve 14 be then opened the mercury may be withdrawn through nozzle 15 without permitting any of the water, sand or gravel to pass into the chamber 13 85 or to pass from the nozzle 15.

It will also be seen that by virtue of the construction herein shown, the mercury may be employed at a plurality of points in a common pipe to trap the gold and that the 90 mercury may be introduced into any of these points or withdrawn from said points without interfering with the action of the mercury in any of the other points.

It is to be understood that the invention 95 is not limited to the precise construction set forth for various changes may be made in the specific embodiment of the invention without departure from the scope of the appended claim.

Having described my invention what I claim is:—

An amalgamator made up of a plurality of goose-neck sections connected end to end

at their lowest portion by crosses, shut-off valves connected to the upper and lower outlets of said crosses, pipe sections projecting upwardly from the uppermost of said valves, pipe sections projecting downwardly from the lowermost of said valves, shut-off valves at the lower ends of the last named pipe sections and shut-off valves at

the upper ends of the first named pipe sections.

In testimony whereof I affix my signature in presence of two witnesses.

EARL P. MAYHEW.

Witnesses:

CHARLES RIEVELEY,
J. C. HIZAR.
